(57) **CLAIM**

The ornamental design for a hub portion of a pair of jaws for a tool, as shown and described.

DESCRIPTION

FIG. 1 is an isometric view from the upper right front of a hub portion of a pair of jaws for a tool, including my new design, wherein portions of a pair of pliers jaws shown in broken line are included merely for illustrative purposes and form no part of the claimed design;

FIG. 2 is an isometric view from the lower left rear of the hub portion of a pair of jaws for a tool shown in FIG. 1, wherein the portions of the pair of pliers jaws shown in broken line are included merely for illustrative purposes and form no part of the claimed design;

FIG. 3 is a right side elevational view thereof, wherein the portions of the pair of pliers jaws shown in broken line are included merely for illustrative purposes and form no part of the claimed design;

FIG. 4 is a top plan view thereof, wherein the portions of the pair of pliers jaws shown in broken line are included merely for illustrative purposes and form no part of the claimed design;

FIG. 5 is a bottom plan view thereof, wherein the portions of the pair of pliers jaws shown in broken line are included merely for illustrative purposes and form no part of the claimed design; and,

FIG. 6 is a left side elevational view thereof, wherein the portions of the pair of jaws for a tool shown in broken line are included merely for illustrative purposes and form no part of the claimed design.
